UNITED STATES PATENT OFFICE.

HARRY A. W. SPENCER, OF NEW YORK, N. Y.

TEMPORARY CLOSURE DEVICE FOR WATER-CLOSET BOWLS, &c.

No. 906,077.

Specification of Letters Patent.

Patented Dec. 8, 1908.

Application filed December 20, 1907. Serial No. 407,359.

To all whom it may concern:

Be it known that I, HARRY A. W. SPENCER, a citizen of the United States, residing in the borough of Manhattan, city, county, and 5 State of New York, have invented certain new and useful Improvements in Temporary Closure Devices for Water-Closet Bowls, &c., of which the following is a specification.

My improved closure device is intended 10 for use temporarily during the installation of plumbing in buildings in course of construction, where houses or apartments are unoccupied, or in public or other places where plumbing is out of order. Plumbers 15 are particularly subjected to annoyance and delay by reason of the premature or improper use of water closets before they are properly connected up; by reason of the bowls being stood upon before they are properly set in 20 position and the bowls being in various other ways subjected to abuse which results in inconvenience and loss.

In order to be practically and commercially successful a closure of this character 25 must be much less complicated and expensive than those heretofore designed for the purpose in so far as I am aware, and the object of my invention is to afford a comparatively simple, inexpensive device for the 30 purpose which may not only be quickly and conveniently applied to seal a water closet bowl temporarily, but which will also prevent the use of the latter as a step, stand or support, for extraneous objects.

35 The invention consists in the combination, construction and arrangement of parts hereinafter described and claimed specifically.

In the accompanying drawings, Figure 1, is a top view of a water closet bowl to which 40 one of my improved closure devices has been applied; Fig. 2, a transverse vertical sectional elevation on plane of line 2—2—Fig. 1; Fig. 3, is a longitudinal sectional elevation upon plane of line 3—3—Fig. 1; Fig. 45 4, is a top view of the clamp bar; Fig. 5, a view of a key wrench suitable for use in connection with my improved closure device.

B represents a wash bowl of any ordinary 50 and well known construction having the usual inturned flange b.

C is a temporary emergency cover preferably stamped out of a single piece of sheet

metal. This cover is convex externally of an inclination or curvature sufficiently steep to 55 prevent a person from standing thereon or using the cover as a rest or support for extraneous objects. It is preferably formed with flaring edges c, c, to extend over the curved upper rim of the water closet bowl B, 60 except at its back portion which fits over the flat back portion b', of the bowl,—said back portion of the cover c', being of preferably uniform curvature or inclination, as indicated in Fig. 3. At the front and sides, 65 where formed with the flaring edges c, the latter merge into the body of the cover without angle or offset sufficient to afford a foothold, and will be readily understood by reference to Fig. 2. The cover C is formed at 70 its apex or center with a recess or depression c², to receive and accommodate the head s, of a screw S, the body of which extends through a perforation c³, in the floor of the said recess c². The recess is of greater depth 75 than the height of the screw head so that access can only be had to the latter by means of a special key K made for the purpose and fitting within the recess c², when applied to the screw head. 80

T is a transverse clamp bar of such length that the ends t, t, fit under the inturned flanges b, of the water closet bowl B, when the said clamp bar is placed in position across the lesser diameter thereof. As, in 85 general practice and trade, water closet bowls of the different standard sizes vary less than an inch in transverse diameter, the length of the transverse clamp bar T and the lesser diameter of the cover C, may 90 readily be made to include and be applicable to any and all the water closet bowls in ordinary use,—the minimum length of bar and diameter of cover being available for use on the maximum size of water closet 95 bowls. The transverse clamp bar T is virtually a nut bar, being formed with a central perforation t', which is tapped to afford a female thread for engagement with the male thread of the screw S. 100 This threaded central nut portion t², of the transverse clamp bar T is preferably on a higher plane than that of the ends t, t, thereof when the bar is in a vertical position, as in use so that a relatively short 105 screw S may be used,—the transverse clamp-

ing bar constituting virtually an inverted U-shaped clamping nut.

In practice the parts are assembled ready for use, the transverse clamp or nut bar T being coupled to the convex cover by means of the screw S. In applying the cover to a closet bowl the bar T is adjusted on the screw S to allow the ends t, t, of the bar T to swing under the inturned flanges b, of the bowl, when the screw is tightened by means of the special key K so as to clamp the cover rigidly upon the bowl. In the absence of the special key K or equivalent device, the bowl cannot then be tampered with; nor can the cover be stood upon or otherwise used as a support for articles of weight. Hence if the bowl has just been placed upon its foundation, the setting of the latter cannot be impaired, nor can the bowl be broken by reason of its use as a stand or step, or as a support for extraneous objects. Furthermore the bowl cannot be surreptitiously used for any improper purpose unless a suitable key is available, and as this is presumably in possession of the plumber or person in charge, it is obvious that under ordinary conditions ample protection is afforded.

Ordinarily considerable damage and loss results during the installation of water closets in large new apartment buildings, especially in cold weather by reason of the freezing of liquids surreptitiously introduced into them, or from their becoming foul or clogged by the introduction of solid matter, so that the cost of replacement, or of time and labor involved in rectifying such abuses becomes a serious item of expense. All these objections I overcome by a simple, cheap contrivance which may be discarded after use without material loss as compared with that involved in the illegitimate use of the bowl as hereinbefore intimated.

45 What I claim as my invention and desire to secure by Letters Patent is,

1. A temporary closure device for water closet bowls consisting of an externally convex cover fitting over the top of the bowl, the convexity of external surface of the cover being sufficient to prevent the use of the cover as a standing place, a clamping screw passing through a perforation in said cover with its head bearing on top thereof, and a transverse clamping bar formed with a female screw thread engaging said clamping screw and having its ends adapted to fit under the inturned flange of the rim of the water closet bowl, for the purpose described.

60 2. A temporary closure device for water closet bowls consisting of an externally convex cover fitting over the top of the bowl, the convexity of the external surface of the

cover being sufficient to prevent the use of the cover as a standing place and it being 65 formed with a central depression or recess, a clamping screw passing through a perforation in the floor of said recess and bearing against said floor, and a transverse clamping bar formed with a female screw thread engaging said clamping screw and having its ends adapted to fit under the inturned flange of the rim of the water closet bowl, for the purpose described.

3. A temporary closure device for water 75 closet bowls consisting of an externally convex cover fitting over the top of the bowl, the convexity of external surface of the cover being sufficient to prevent the use of the cover as a standing place, a clamping 80 screw passing through a perforation in said cover with its head bearing on top thereof, and an inverted U-shaped transverse clamping bar formed with a central female screw thread engaging said clamping screw and 85 having its ends adapted to fit under the in-turned flange of the rim of the water closet bowl, for the purpose described.

4. A temporary closure device for water 90 closet bowls consisting of an externally convex cover formed with flaring edges and fitting over the top of the bowl, the convexity of external surface of the cover being sufficient to prevent the use of the cover as a standing place, a clamping screw passing 95 through a perforation in said cover with its head bearing on top thereof, and a transverse clamping bar formed with a female screw thread engaging said clamping screw and having its ends adapted to fit under the 100 inturned flange of the rim of the water closet bowl, for the purpose described.

5. A temporary closure device for water 105 closet bowls consisting of an externally convex cover stamped out of a single piece of sheet metal, and fitting over the top of the bowl, the convexity of external surface of the cover being sufficient to prevent the use of the cover as a standing place, a clamping 110 screw passing through a perforation in said cover with its head bearing on top thereof, and a transverse clamping bar formed with a female screw thread engaging said clamping screw and having its ends adapted to fit under the inturned flange of the rim of the 115 water closet bowl, for the purpose described.

6. A temporary closure device for water 120 closet bowls, consisting of an externally convex cover fitting over the top of the bowl, the convexity of the external surface of the cover being sufficient to prevent the use of the cover as a standing place, and means for clamping said cover to the bowl for the purpose described.

7. A temporary closure device for water 125 closet bowls, consisting of an externally con-

convex cover fitting over the top of the bowl, the convexity of the external surface of the cover being sufficient to prevent the use of the cover as a standing place, a transverse 5 clamping bar having ends adapted to fit under the inturned flange of the rim of the water closet bowl, a screw connected with said transverse clamping bar and projecting

through the cover, and externally operated means bearing against the top of the cover 10 for utilizing said screw to secure the cover to the bowl, for the purpose specified.
